UNITED STATES PATENT OFFICE.

JACOB E. NEAHR, OF NEW YORK, N. Y.

MATCH SAFE.

Application filed May 10, 1919. Serial No. 296,082.

To all whom it may concern:

Be it known that I, JACOB E. NEAHR, a citizen of the United States, residing in the city, county, and State of New York, have invented certain new and useful Improvements in Match Safes, of which the following is a specification.

This invention relates to combined match-safes, match-strikers and accessories, and is illustrated in connection with a combined match-safe and striker of the kind disclosed in my Patent No. 1,432,889, dated October 24, 1922.

In said patent is illustrated a safe to hold a small number of matches; a coil, consisting of windings of match-igniting strip, surrounding the safe. One of the objects of the present invention is to make it convenient to supply the safe with matches; and to this end I mount the match-safe upon a base which comprises a magazine for the matches. This is done in such a manner that the matches in the magazine are safeguarded, while access may be readily had thereto for the purpose of securing a supply wherewith to replenish the match-safe. The weight of the magazine enables it to do service as a base or support for the match-safe at the match-striking operation.

The magazine is illustrated in the form of a box provided with a lid; and the match-safe is mounted upon the lid, to be taken off therewith.

The magazine is of such form and capacity that there may be conveniently deposited or fitted therein a pasteboard tray, in which the matches are usually packed for the market. Such boxes are usually in the form of oblong trays, which are slidden into casings open at their ends, in which condition they are filled with matches and marketed. In using the novel magazine, such tray with its matches will be slidden out from the casing, and dropped into the magazine; and then the cover will be replaced, with its attached match-safe. Upon merely removing the cover, the matches in the magazine become accessible.

One of the objects of the invention is to prevent spurious matches from being supplied to the magazine, and to this end the magazine is provided with a special support for the tray, and the tray is formed with a special contour to fit the support, so that spurious boxes cannot be successfully employed; the magazine being unprovided with

a bottom, so that matches cannot be loosely dumped therein, but must be within their trays or containers as they are placed in the magazine.

Preferably the lid or cover of the magazine is made double, comprising both a top and a floor portion, to form a box or receptacle into which matches and ashes may be dropped through openings in the cover. Provision is made to facilitate the dumping of the contents from the tray when required.

In the preferred form of the invention, the bottom of the ash-receiver is made sloping from the ends to the middle, so that matches deposited in the openings in the lid will not accumulate beneath said openings and thereby choke the same, but will slide or settle towards the bottom portion of the floor, and hence away from the openings, leaving the latter clear.

Other features and advantages will hereinafter appear.

In the accompanying drawings,

Figure 1 is a perspective view of a match-safe, striker, ash box and magazine, illustrating the present improvements in one form; the parts being broken away to disclose the interior.

Figure 2 is a part-sectional side elevation of the structure.

Figure 3 is a perspective of the novel match tray in its open-ended casing.

Figure 4 illustrates the manner of using a pasteboard match tray of ordinary construction.

Figure 5 is a perspective view and Figure 6 a sectional elevation of the preferred form of the invention, showing the ash-receiver provided with a bottom which slopes from the ends to the middle.

As set forth in said patent, the matches stand in a safe 11, having a floor 12, and having threads 13 rolled into its lower end, to screw into a threaded neck 14 rising from a cover 15 provided upon a match magazine 16, which constitutes the base for the match-safe and striker. Surrounding the lower part of said match-safe and said neck is a tubular pedestal or shell 17, which is held down upon the cover by means of a flange or rim 18 provided upon the top of the match-safe 11; and upon this shell are arranged the windings of match-striking material 19.

Within said tray is placed a pasteboard tray 20 comprising ends 21, sides 22 and

bottom 23, and filled with matches 24. This box may be supplied in a rectangular pasteboard casing 25 having open ends, and of the usual dimensions in which matches are supplied to the market in bulk. The tray 20 may be loosely enclosed in the magazine 16, as illustrated at Figure 2. The magazine, which is of sheet-metal, has no floor, but supports the tray at its ends by means 10 of in-turned tongues 26, these tongues projecting inwardly and downwardly, and of sufficient dimensions to support the match tray. The latter has its lower corners beveled at 27 as shown, so as to correspond with 15 the inclination of the supporting tongues, so that the tray may sink to the bottom of the magazine. The floor of the tray supports the matches. Since the magazine has no floor, it is, of course, impracticable to dump 20 matches loosely into the magazine, whereby a protection is afforded against the use of inferior matches; and if it were attempted to use trays of ordinary make, which do not have the provision of the beveled end corners 25 for resting upon the supporting tongues, said trays would not be found to sink to the proper depth, and would stand so high that the cover could not be successfully placed upon the magazine. The magazine may 30 have a bead 28 rolled into its lower edge for resting upon a table, and for stiffness.

In the front of the magazine may be formed a window 29 through which may be read an advertisement or legend 30 printed upon the side of the pasteboard match tray, thus increasing the usefulness of the latter, since it has not been the practice to print upon the sides of these match trays heretofore, because said sides were always 40 covered up in the casings.

The cover may be double, or have a false bottom 31, which may constitute the floor of an ash receptacle, and may have end and side walls 32, 33 soldered or otherwise connected to the cover; said ash receptacle extending within the magazine, and the cover having a flange 34 extending down over the top edge of the magazine all the way around the same. In said cover may be formed 45 openings 35, through which burned matches and ashes may be dropped into the ash receptacle, and at the end of the latter may be formed a discharge opening 36, said opening being normally confined within the magazine, as at Figure 2, so that ashes cannot be spilled from the receptacle, but being useful to discharge the contents of the receptacle when the latter is lifted out from the magazine.

50 At Figure 6 the floor of the ash receiver slopes inwardly at 37 from the opposite sides or ends, sufficiently to permit matches and ashes dropped thereon to gravitate away from the openings 38. These openings are narrow slits, and have enlarged

ends 39. The matches must therefore be dropped through them in a manner to roll down the floor 37; that is, the direction of the slit is crosswise of the direction of the slope of the floor, so that the match must occupy a crosswise position when striking the floor, and hence readily roll down the same. The enlarged ends of the slits afford room for the heads of the matches.

70 Variations may be resorted to within the scope of the invention, and portions of the improvements may be used without others.

Having thus described my invention, I claim:

1. As a new article of manufacture, a combined match-safe and match-striker, a match magazine having a lid upon which said combined match-safe and striker is mounted, and a tray filling said magazine and filled with matches from which the safe 80 may be replenished, said magazine having no bottom, and provided with interior supports for the tray, and the tray formed with special contour to fit said supports.

2. As a new article of manufacture, a combined match-safe and match-striker, a match magazine having a lid upon which said combined match-safe and striker is mounted, and a tray filling said magazine and filled with matches from which the safe 90 may be replenished, said magazine having no bottom, and provided with opposite inwardly and downwardly inclined supports for the lower corners of the tray, and the tray having lower beveled corners to fit upon 95 said supports.

3. A match magazine having a lid to which is fixed a match-safe, said magazine being bottomless, and having inwardly projecting tongues to support the bottom corners of a match tray, said tongues inclining downwardly from the opposite portions of the magazine.

4. As a new article of manufacture, a combined match-safe and match-striker, and a base therefor in the form of a magazine for matches, said magazine comprising a lid, and said combined match-safe and striker being mounted upon said lid, said lid being 110 in the form of a box to form a receptacle for 115 ashes.

5. As a new article of manufacture, a combined match-safe and match-striker, and a base therefor in the form of a magazine for matches, said magazine comprising a lid, and said combined match-safe and striker being mounted upon said lid, said lid being 120 in the form of a box to form a receptacle for ashes, the lid having an opening for the deposit of ashes in said receptacle.

6. As a new article of manufacture, a combined match-safe and match-striker, a base therefor in the form of a magazine for matches, said magazine comprising a lid, and said combined match-safe and striker 130

- being mounted upon said lid, and a receptacle for ashes underlying said lid at the top of the magazine, and comprising a floor and sides and ends, and being provided with 5 a discharge opening at one end.
7. As a new article of manufacture, a combined match-safe and match-striker, a base therefor in the form of a magazine for matches, said magazine comprising a lid, and 10 said combined match-safe and striker being mounted upon said lid, and a receptacle for ashes underlying said lid at the top of the magazine, and comprising a floor and sides and ends, said lid having a downwardly-projecting flange extending around the magazine, said receptacle being provided with 15 a discharge opening in one of its walls.
8. As a new article of manufacture, a combined match-safe and match-striker, and a 20 base therefor in the form of a magazine for matches, said magazine comprising a lid, and said combined match-safe and striker being mounted upon said lid, said magazine being of such form and capacity that there may be 25 fitted therein a pasteboard tray in which the matches are usually marketed, said magazine having a window through which may be exhibited a legend or advertisement printed upon the side of the tray.
- 30 9. As a new article of manufacture, a combined match-safe and match-striker, a match magazine having a lid upon which said combined match-safe and striker is mounted, and a tray filling said magazine and filled with 35 matches from which the safe may be replenished, said magazine having no bottom, and provided with interior supports for the tray, and the tray formed with special contour to fit said supports, said magazine having a 40 window through which may be exhibited a legend or advertisement printed upon the side of the tray.
10. As a new article of manufacture, a combined match-safe and match-striker, and a 45 base therefor in the form of a magazine for matches, said magazine comprising a lid, and said combined match-safe and striker being mounted upon said lid, said lid being in the form of a box, to form a receptacle
- for ashes, the lid having an opening for the 50 deposit of ashes in said receptacle, said receptacle comprising a floor which slopes away from said opening.
11. As a new article of manufacture, a combined match-safe and match-striker, and a 55 base therefor in the form of a magazine for matches, said magazine comprising a lid, and said combined match-safe and striker being mounted upon said lid, said lid being in the form of a box, to form a receptacle for 60 ashes, the lid having at its ends openings for the deposit of ashes and burned matches, and said receptacle comprising a floor which slopes down towards the middle of the receptacle.
12. As a new article of manufacture, a combined match-safe and match-striker, and a 65 base therefor in the form of a magazine for matches, said magazine comprising a lid, and said combined match-safe and striker being mounted upon said lid, said lid being in the form of a box, to form a receptacle for ashes, the lid having an opening for the deposit of 70 ashes in said receptacle, said receptacle comprising a floor which slopes away from said opening, said opening in the form of a narrow slit set crosswise of the direction in which the floor slopes.
13. As a new article of manufacture, a combined match-safe and match-striker, and a 75 base therefor in the form of a magazine for matches, said magazine comprising a lid, and said combined match-safe and striker being mounted upon said lid, said lid being in the form of a box, to form a receptacle for 80 ashes, the lid having an opening for the deposit of ashes in said receptacle, said receptacle comprising a floor which slopes away from said opening, said opening in the form of a narrow slit set crosswise of the direction in 85 which the floor slopes, said slit having an enlarged end for the passage of the heads of the matches.
